UNITED STATES PATENT OFFICE.

GEORGE A. HINES, OF BRATTLEBOROUGH, VERMONT, ASSIGNOR OF ONE-HALF TO WALTER H. CHILDS, OF SAME PLACE.

CHEMICAL TELEGRAPH.

SPECIFICATION forming part of Letters Patent No. 250,147, dated November 29, 1881.

Application filed August 23, 1881. (No model.)

To all whom it may concern:

Be it known that I, GEORGE A. HINES, of Brattleborough, in the county of Windham and State of Vermont, have invented a new and useful Improvement in Chemical Telegraphs, which improvement is fully set forth in the following specification, reference being had to the accompanying drawings.

This invention relates to a system of chemical telegraphy in which the proper makes and breaks in the circuit at the transmitting instrument, which makes the signals to be recorded at the receiving-instrument, are made through the medium of a strip or fillet of non-conducting material having its edges notched or serrated, said notches or serratures corresponding to such telegraphic signals or characters as may be desirable. They may be arranged according to the Morse system or in accordance with such codes as may be devised; furthermore, in connection with the above, the necessary apparatus for utilizing to the desired end the peculiarities of the serrated strip or fillet.

The object of my invention is to provide an improved method by which messages may be rapidly transmitted over a single wire, thus reducing the cost of construction and maintenance, and also obviating what has come to be regarded as objectionable in various ways—the multiplicity of wires necessary for a large business under the old system.

My invention consists, first, of a strip or fillet of non-conducting material having its edges notched or serrated, such notches or serratures corresponding to such telegraphic characters or signals as may be desired or devised; second, of a guide-box, in combination with the serrated strip or fillet, for retaining the same in its proper position and direction for the accomplishment of the purpose for which it is designed; third, of vibrating circuit-closers having springs for giving them the requisite tension, and also having adjusting devices, in combination with the serrated fillet and guide-box; fourth, of what may be denominated "line-keys," so arranged in combination with the foregoing elements as to transmit to a main-line wire such signals or impulses as may be imparted to them from a suitable battery through the medium of the said elements; fifth,

in connection with the foregoing elements, together with feed-rolls for giving the fillet its proper motion through the guide-box, a main-line wire connecting the transmitting-instrument at either end of the line with the receiving-instrument at the other; sixth, in combination with the foregoing elements, a recording-instrument, the different elements of which will be hereinafter more fully set forth.

The invention will be more fully understood by reference to the accompanying drawings, forming a part of this specification, in which—

Figure 1 is a plan of the transmitting apparatus; Fig. 2, a side elevation of the same, and Fig. 3 an end elevation; Fig. 4, a sectional plan, showing a second device for what I denominate a "line-key." Fig. 5 is a plan of the recording-instrument; Fig. 6, a side elevation of the same, and Fig. 7 an end elevation. Figs. 8 and 9 show modifications of the serrated fillet.

The same letters in all the different figures refer to the same parts.

A is the base of the transmitting-instrument. B is the guide-box. This box is slotted longitudinally and of just sufficient width and depth to receive the serrated fillet C C C, which is drawn through the slot in the guide-box B by means of the feed-rolls a and a'. The ends of the slot in the box B are rounded outward, as at b", Figs. 3 and 4, so as to present no obstacle to the free movement of the fillet C C C.

D and D' are the circuit-closers, one on each side of B. These are composed of four parts—viz., main bars D and D', hubs I I, (seen to the best advantage in Fig. 4,) pawls d and d', and tension-springs F and F'. The pawls d and d' enter slots b b' in guide-box B, to enable them to come in contact with the edges of the serrated fillet C C C. D and D' are supported by and vibrate on the studs E E', and are held down in place by the thumb-nuts e and e'. The tension-springs F and F' are adjusted by the thumb-screws f and f'. These have small drums or cylinders f" f''' on their bodies eccentric with their axes, forming cams, thus providing to F F', as constructed, the means for their requisite tension.

G and G' are the "line-keys," so called, supported by studs g and g', and adjusted to the

necessary position for impact with the circuit-closers D D' by means of the thumb-screws g'' and g''', having cams g⁴ and g⁵, the same in construction as f f'' and f' f''''. To the studs g g' is connected the main-line wire, and to the studs E E' are connected the battery wires or wire, as the case may be.

H, Fig. 4, is a line-key of different construction from those described above. It consists of a metallic piece embedded in the slot of the guide-box B, the serrated fillet C C C passing over it. It is forked at the slots b b', in order that it at the proper times may be in contact with the pawls of the circuit-closers D D'. It projects beyond the end of the box B, and is provided with a stud, h, for connection with main-line wire.

In Fig. 5, J is the base of the recording-instrument; L, a guide-box, slotted for the admission and free longitudinal movement of a chemically-prepared fillet of paper, O O O. Motion is given to this by means of the feed-rolls M m.

N is a vertical frame on base J for supporting stud n, in which is confined the pen or style P, to which is attached the receiving end of the main-line wire. The box L has an aperture at the top, so that the point of the pen or style P can come in contact with the chemical paper O O O, and immediately under the point of P is a metallic bed-piece or ground-plate, R, slightly convex toward the paper which runs over it, and having a projection, R', outside of box L, with stud r for attaching a ground-wire.

In Fig. 1, I have, for the sake of avoiding confusion of lines, shown the line-wires 1 and 2 as proceeding outward from the studs g g'; but in practice they should be connected together and with the main-line as near to g g' as is practicable or convenient.

The feed-rolls a a' and M m may have the proper motion imparted to them by means of any suitable mechanical device, and their motions should be approximately isochronous.

C C and C, Figs. 8 and 9, are some modifications of the serrated fillet. The serratures may be upon one side or the other of the fillet, with a current of one polarity, or upon both sides with a current of one polarity, or upon both sides with currents of intermittent polarity, or upon both sides with currents of alternate polarity.

From the foregoing I think the operation of the invention will be fully understood. The serrated fillet, having been properly prepared in accordance with the principles herein set forth, is drawn through the guide-box by means of the feed-rolls. The pawls of the circuit-closers fall into the serratures as they come opposite to them, thus making contact with the line-keys, as at t, Fig. 1, and at t'', Fig. 4, thus imparting the current to the main-line wire, and through it to the pen or style

65 of the recording-instrument through the chemical paper to the ground-plate, and thence to

the ground, each consecutive current or impulse making a legible mark on the paper O O O, which may afterward be translated in accordance with the prearranged code.

The serrated fillet might be of either conducting or non-conducting material. If of conducting material, the pawls of the circuit-closers should be non-conductors, and the form of line-keys G G' only would be practicable; but as a measure of economy and utility paper of a medium thickness would be the best material, and the serratures could be easily and rapidly made in the edges of the fillet by means of a punch or press devised for the purpose. It will also readily be seen that contact could be made when the pawls are receding from the serratures; but the method already described I consider the most practicable.

I of course lay no claim to making legible marks on prepared paper by passing a current of electricity through it; but

What I do claim, and what I desire to secure by Letters Patent, is—

1. A strip or fillet of non-conducting material having its edges notched or serrated, said notches or serratures corresponding to such telegraphic characters or signals as may be desired or devised, for the purpose as hereinbefore set forth.

2. In combination with the serrated fillet, a guide-box slotted for the admission and guidance of the fillet, and having its sides slotted vertically for the admission of circuit-closers to the edge or edges of the serrated fillet, substantially as shown.

3. The vibrating circuit-closers D and D', as described, in combination with the serrated fillet and guide-box, substantially as shown.

4. The line-keys G and G', as described, in combination with the circuit-closers D and D', the serrated fillet, and guide-box, substantially as shown.

5. In combination with the serrated fillet, guide-box, circuit-closers, line-keys, and feed-rolls, a main-line wire connecting these transmitting elements at either end of the line with the receiving elements at the other, substantially as shown.

6. A recording-instrument consisting of a fillet or strip of chemically-prepared paper, a guide-box for the same, a pen or style connected with the main-line wire, a ground plate and wire, and feed-rolls, in combination with the serrated fillet, guide-box for the same, circuit-closers, line-keys, main-line wire, and feed-rolls, substantially as before shown and described.

In testimony that I claim the foregoing I have hereunto set my hand in the presence of the subscribing witnesses.

GEORGE A. HINES.
